Primary Examiner — Carol P Rademaker(74) *Attorney, Agent, or Firm* — Abelman, Frayne & Schwab(57) **CLAIM**

The ornamental design for a perfume bottle, as shown and described.

DESCRIPTION

FIG. 1 is a front elevational view showing my new design; FIG. 2 is a rear elevational view thereof; FIG. 3 is a left side elevational view thereof, the right side elevational view being identical; FIG. 4 is a top plan view thereof; and, FIG. 5 is a bottom plan view thereof. The broken lines shown on the bottom surface in the FIG. 5 drawing view are included for the purpose of illustrating environmental structure and form no part of the claimed design.
